UNITED STATES PATENT OFFICE.

LAURENCE C. GRAHAM, OF WHIGHAM, GEORGIA.

DENTAL-CROWN-SWAGING MACHINE.

No. 881,574.

Specification of Letters Patent. Patented March 10, 1908.

Application filed November 6, 1906. Serial No. 342,280.

To all whom it may concern:

Be it known that I, LAURENCE C. GRAHAM, a citizen of the United States, residing at Whigham; in the county of Grady and State 5 of Georgia, have invented a new and useful Dental-Crown-Swaging Machine, of which the following is a specification.

This invention relates to machines of that 10 class employed by dentists in the manufacture of tooth crowns from gold or other ductile metals.

The principal object of the invention is to 15 provide a machine of very simple construction in which interchangeable dies may be employed for the formation of crowns for both the posterior and anterior teeth, and in which the crowns may be stamped directly from a sheet of gold or other material, a sufficient area of the sheet being cut by the machine 20 immediately in advance of the swaging operation to form the desired article.

A further object of the invention is to provide a machine of very simple construction in which the dies may be readily interchanged, the dies being provided with identifying marks, such, for instance, as numerals, in order that the dentist may determine 25 with exactness the size and shape of the crowns to be made.

With these and other objects in view, as will more fully hereinafter appear, the invention consists in certain novel features of construction and arrangement of parts, herein-after fully described, illustrated in the accompanying drawings, and particularly pointed out in the appended claims, it being understood that various changes in the form, proportions, size and minor details of the structure may be made without departing 35 from the spirit or sacrificing any of the advantages of the invention.

In the accompanying drawings:—Figure 1 is a sectional elevation of a crown swaging machine constructed in accordance with the 45 invention. Fig. 2 is a sectional plan view of the same on the line 2—2 of Fig. 1. Fig. 3 is a plan view of the lower or male die.

Similar numerals of reference are employed to indicate corresponding parts throughout the several figures of the drawings.

The machine includes a base 10 from which rises a frame 11 that is provided at the center with a vertically disposed opening for the 55 passage of a plunger 15, and at the top of the frame is arranged a pair of ears 16 carrying a

cross pin 17 on which is pivoted a cam lever 18, the cam being arranged to engage a plate 19 that is secured to the upper end of the rod 15. This plate is preferably rectangular in 60 form, having parallel opposite sides for engagement with the inner faces of the lugs 16 in order to hold the plunger rod from rotative movement. The rod is normally maintained in elevated position by two or more 65 helical compression springs 20, the lower ends of which are seated in recesses formed in the top of the frame, while the upper ends of said springs fit around guiding pins 21 depending from the lower face of the plate 19. 70

In the lower portion of the plunger rod is a recess for the reception of the carrying stem 23 of a female die 24, the latter being provided with diametrically opposite ribs 25 that fit in grooves formed in the lower face of 75 the plunger rod in order to prevent rotative movement of the die. In order to permit the ready changing of the dies, a spring held locking pin 28 is employed, said pin having an outer knob or handle 29, and being normally held in stem engaging position by a 80 spring 30. When the pin is pulled outward, the stem is released, and the die may be readily removed and another placed in its stead. The dies are preferably provided 85 with small panels 32, on which the number or other designating mark may be placed.

The central portion of the base plate is provided with a boss 33 having a dove tailed recess for the reception of the similarly shaped male die 35, and at the edge of the male die is a rib 34 forming in connection with the outer edge of the female die a shearing face by which the sheet of gold or other metal may be cut to the exact size necessary for the 90 formation of the crown. Upon the upper face of the die 35 within the cutting rib 34 are two projections 36 of less height than said rib. Immediately above these projections are depressions 37 in a female die 24. 95 These elevations and depressions are the dies proper and between them the front and rear halves of the tooth crown are formed from the plate of sheet metal cut out from a piece of stock by the rib 34. These two portions of the crown are swaged side by side from the same sheet of metal and when they are to be finished, the front and rear half 100 will be separated from each other by cutting the plate and finishing up the crown in the 110 usual manner.

In use the sheet of gold or other metal is

placed over the male die, and the lever 18 is turned for the purpose of forcing the female die down, the first action being to sever from the sheet a small piece of gold of sufficient size to form the front and back portions of the crown. This small piece of gold is then forced down over the die, and is properly shaped. The surfaces of the dies are preferably made so smooth as to prevent the formation of ridges or cavities which would serve for the lodgement of particles of food, while the crowns are in place in the mouth.

I claim:—

A manually operable crown swaging 15 vice comprising a base plate having a dovetailed groove, a combined cutting and swaging die disposed therein, a frame carried by the base and provided with a vertical guiding opening in alinement with said die, a pair of 20 pivot ears extending upward from the frame and provided with parallel inner walls, a plunger rod extending through the guiding opening, a plate secured to the top of the

plunger rod, the opposite sides of said plate engaging the side walls of the pivot ears to 25 prevent turning of the plunger, a cam lever arranged to operate on said plate, springs for elevating the plate and rod, the lower end of said rod having a central opening, and being provided with a diametrically extending 30 recess, a movable cutting and swaging die having an integral stem arranged to fit within the opening of the plunger and provided with a pair of ribs arranged to fit within said diametrically extending recess, and a 35 spring actuated locking pin carried by the plunger and arranged to fit within an opening formed in the stem, substantially as specified.

In testimony that I claim the foregoing as my own, I have hereto affixed my signature 40 in the presence of two witnesses.

LAURENCE C. GRAHAM.
